DESIGN FOR A BIRD HOUSE

Charles F. Klein, Stockton, Calif.

Application May 18, 1936, Serial No. 62,701

Term of patent 14 years

To all whom it may concern:

Be it known that I, Charles F. Klein, a citizen of the United States, residing at Stockton, in the county of San Joaquin and State of California, have invented a new, original, and ornamental Design for a Bird House, of which the following is a specification, reference being had to the accompanying drawing, forming a part thereof,

and in which Fig. 1 is a front view of a bird house, showing my new design; Fig. 2 is a side view of the same; and Fig. 3 is a rear view of the bird house.

I claim:

The ornamental design for a bird house, as shown.

CHARLES F. KLEIN.
